COMBINATION SASH AND SCREEN LATCH

Joseph N. Victor, Allentown, Pa.

Application December 15, 1933, Serial No. 702,625

8 Claims. (Cl. 292—218)

This invention relates to latching mechanisms for swinging doors, windows, and the like and relates particularly to latching mechanisms adapted for use in connection with windows of the casement type having, in addition to the main swinging sash, a secondary sash which may be either a glass carrying or a wire screen carrying member.

One purpose of the invention is to provide a novel latching mechanism whereby either or both sash members of a window of the casement type may be securely latched in fully closed position. The invention contemplates the use, in such a mechanism, of a single latching member movably mounted upon the frame, which member is adapted to engage catches positioned on the main and auxiliary sashes respectively, thus eliminating the necessity of using two separate and distinct latching members, reducing the cost of installation of such securing devices, and generally promoting simplicity in the window construction, thus facilitating manufacture and reducing cost.

While the invention is particularly useful in connection with casement windows of the dual sash type, it is by no means limited to use in conjunction with windows but is equally applicable to door constructions in which two doors are mounted upon a single frame for swinging movement. Likewise, in adapting the invention to various types of casement windows or door constructions, it is possible to vary the design and arrangement of its component elements very considerably without departing from the spirit and scope of the invention, as will be appreciated by one skilled in this art.

In the drawing a preferred embodiment of the invention is illustrated by way of example.

Figure 1 is a horizontal section through a window of the casement type having the novel latching mechanism incorporated therein, the main and auxiliary sashes being shown in closed position;

Figure 2 is a section on line 2—2 of Figure 1; Figure 3 is a section on line 3—3 of Figure 2; and

Figure 4 is a perspective view of a housing member within which certain parts of the latching mechanism are retained.

The window selected for purposes of illustration has a frame which may be of usual type in its major particulars, this frame, however, including a novel abutment member 10 extending continuously around the same on its inner surface and which member comprises a common

abutment or stop limiting the swinging movements of both the outer sash 11 and the inner sash 12, this last mentioned sash preferably carrying a screen 13. The outer sash is mounted for swinging movement about a vertical axis upon supporting hinges 14, and the screen carrying sash is supported for swinging movement relatively to the frame and to the sash about a parallel and closely adjacent axis by means of hinges 15. It will be understood, of course, that the sash and screen may be independently manipulated, either or both being moved to open position or either or both maintained in closed position.

To permit operation of the sash without opening the screen, any suitable sash operating mechanism (not illustrated) may be employed. At one point the abutment member 10 is interrupted and a housing member 16, preferably of cast metal, placed in the gap between the adjacent ends of the abutment, this housing being so designed that its outer surfaces 16', 16², and 16³ comprise continuations of the adjacent surfaces of the abutment member, and a portion of the housing extending laterally to lie behind a shoulder 10' of the frame. Within the housing 16 is positioned a pivot pin 17, preferably having threaded engagement with a cylindrical aperture formed in the wall of the housing, and upon this pivot pin is mounted the latch member 18 for rocking movement about the pin in a vertical plane transverse to the window.

Upon the outer end of the rockable latch member 18 is mounted a catch engaging pin 19 which is adapted to engage a catch 20 anchored to the adjacent side rail of the sash 11. Catch 20 is formed as a downwardly opening hook member, the inner edge 20' of which is curved and in reality constitutes a wedging or camming surface, the pin 19 first engaging this surface adjacent the lower end or point of the catch, when the latch member is operated with the sash in not quite fully closed position, the pin 19 traveling upwardly along this surface as the latch member is moved from full-line position (Figure 2) to dotted-line position, and exerting a camming action on the catch tending to draw the sash firmly into contact with the continuous abutment 10.

A second catch is mounted upon the screen member 12, this catch being indicated at 22 and comprising essentially a straight metallic member anchored securely in the rail of the screen with its end projecting into the plane of movement of the latch member. As will be seen from an inspec-

tion of the drawing, the latch member is provided with a curved handle portion 18, which handle portion has terminal shoulders 18² located relatively close to the pivot pin 17. So long as the latch member is in the position shown in full lines in Figure 2, it is completely disengaged from both the catch 20 and the catch 22, but when it is moved from full-line position to dotted line position, it operatively engages both of these catches, the pin 19 engaging catch 20, as before explained, and the shoulder 18² of the latch member descending and engaging the outer surface of catch 22, as indicated in dotted line in Figure 2, thus holding the catch 22 between this shoulder of the latch member and the wall of the housing member 16. By a single rocking movement of the latch member, therefore, both catches may be engaged and both sash members locked in closed position, or both sash members 20 may be unlocked, if already closed, by a single 25 counterclockwise movement of the latch member. Again, the latch member may be manipulated to engage either of the catches alone, as, for instance, when the main sash is in open position the latch member may be operated to engage or 30 disengage the catch 22 of the screen. It will be appreciated that the handle portion 18 of the latch member tapers toward its lower end so that, when lifted to disengaging position as shown in full lines in Figure 2, there is considerable clearance between the end of the catch 22 and the side of the handle as the screen is moved to open position.

By utilizing the combination latching mechanism shown, the cost of fabricating and installing two separate latching mechanisms is avoided, and the device is furthermore inconspicuous and ornamental. By reason of the fact that the housing 16 has the same section as the stop member 10, it may be conveniently applied and, after being affixed, does not project in any manner beyond the stop member to catch clothing, etc. Furthermore, inasmuch as the housing has a portion extending in rear of shoulder 10' of the frame and resting snugly thereagainst, it cannot be moved or dislodged by the pull of catch 20 as lever 18 is manipulated to effect the final closure of the sash 11.

Having thus described the invention, what is claimed as new and desired to be secured by Letters Patent is:

1. A latching mechanism adapted to be used with windows of the casement type having two swinging sashes which are disposed in parallel planes when closed, comprising, in combination, 55 two catch members adapted to be secured respectively to the free edges of such sashes, a support adapted to be secured to the window frame member and having a portion which lies between the sashes when the sashes are in closed position, and a latch member pivotally mounted upon said support for swinging movements about an axis parallel to the planes of the sashes when closed and having spaced catch engaging portions which 60 may be brought into latching engagement with both catches when moved in one direction and which may be moved in the opposite direction to disengage such catches.

2. A latching mechanism adapted to be used 70 with windows of the casement type having two swinging sashes which are disposed in parallel planes when closed, comprising, in combination, two catch members adapted to be secured respectively to the free edges of such sashes, a support 75 adapted to be secured to the window frame

member and having a portion which lies between the sashes when the sashes are in closed position, and a latch member pivotally mounted upon said support and having spaced catch engaging portions which may be brought into engagement with both catches when moved in one direction and which may be moved in the opposite direction to disengage such catches, said latch member being positioned so as to lie beyond the free edge of one sash and the catch associated with 10 said sash projecting beyond the edge thereof and into the path of movement of the latch member.

3. A latching mechanism adapted to be used with windows of the casement type having two swinging sashes which are disposed in parallel planes when closed, comprising, in combination, two catch members adapted to be secured respectively to the free edges of such sashes, a support 15 adapted to be secured to the window frame member and having a portion which lies between the sashes when the sashes are in closed position, and a latch member pivotally mounted upon said support to rock about an axis intermediate and parallel to the planes of the sashes when closed, said latch member having a portion which lies between the 20 sashes when the sashes are in closed position, and a latch member pivotally mounted upon said support to rock about an axis intermediate and parallel to the planes of the sashes when closed, said latch member having spaced catch 25 engaging portions which may be brought into latching engagement with both catches when rocked in one direction and which may be rocked in the opposite direction to disengage such catches. 30

4. A latching mechanism adapted to be used with windows of the casement type having two swinging sashes which are disposed in spaced parallel planes when closed and adapted to open in opposite directions, comprising, in combination, 35 a latch member pivotally mounted on the window frame adjacent the free edges of said sashes to rock about an axis intermediate of and parallel with the planes of said sashes when closed, a catch member adapted to project from the free edge of each sash adjacent said latch member, and spaced catch engaging portions on said latch member which may be brought into latching engagement with both of said catch members when said member is moved in one direction and disengaged from such catch members when moved in the opposite direction. 40

5. A latching mechanism adapted to be used with windows of the casement type having two swinging sashes which are disposed in spaced 50 parallel planes when closed and adapted to open in opposite directions, comprising, in combination, a latch member pivotally mounted on the window frame adjacent the free edges of said sashes to rock about an axis intermediate of and parallel with the planes of said sashes when closed, a catch member adapted to project from the free edge of each sash adjacent said latch member, and spaced catch engaging portions on 55 said latch member which may be brought into latching engagement with both of said catch members when said member is moved in one direction and disengaged from such catch members when moved in the opposite direction, said catch engaging members being disposed on opposite sides of said axis whereby one of them is swung upwardly into engagement with its associated catch member and the other is at the same time swung downwardly into engagement with its catch member. 60

6. A latching mechanism adapted to be used with windows of the casement type having two swinging sashes which are disposed in spaced parallel planes when closed and adapted to open in opposite directions, comprising, in combina- 75

- tion, a latch member pivotally mounted on the window frame adjacent the free edges of said sashes to rock about an axis intermediate of and parallel with the planes of said sashes when closed, a catch member adapted to project from the free edge of each sash adjacent said latch member, and spaced catch engaging portions on said latch member which may be brought into latching engagement with both of said catch members when said member is moved in one direction and disengaged from such catch members when moved in the opposite direction, one of said catch members adapted to project outwardly from one of said sashes in the plane of said sash so as to intersect the plane of movement of said latch member, the other of said catch members adapted to project inwardly transversely of the plane of said sashes and parallel with the plane of movement of said latch member.
- 5 20 7. A latching mechanism adapted to be used with windows of the casement type having two swinging sashes which are disposed in parallel planes when closed, comprising, in combination, two catch members adapted to be secured respectively to the free edges of such sashes, a support adapted to be secured to the window frame member and having a portion which lies between the sashes when the sashes are in closed position, a latch member pivotally mounted upon said support and having spaced catch engaging portions which may be brought into latching engagement with both catches when moved in one direction and which may be moved in the opposite direction to disengage such catches, said support being formed with a recess adapted to receive one of said catch members and to house the cooperating catch engaging portion, an abutment portion on said support adapted for contact with the associated sash, and another abutment surface on said support adapted to be contacted by the other of said catch members when its associated sash is closed, said last named catch member being thus adapted to be retained between said surface and the other of said catch engaging portions of the latch member.
- 10 15 25 30
8. A latching mechanism adapted to be used with windows of the casement type having two swinging sashes which are disposed in parallel planes when closed, comprising, in combination, two catch members adapted to be secured respectively to the free edges of such sashes, a support adapted to be secured to the window frame member and having a portion which lies between the sashes when the sashes are in closed position, a latch member pivotally mounted upon said support and having spaced catch engaging portions which may be brought into latching engagement with both catches when moved in one direction and which may be moved in the opposite direction to disengage such catches, said support being formed with a recess adapted to receive one of said catch members and to house the cooperating catch engaging portion, an abutment portion on said support adapted for contact with the associated sash, and another abutment surface on said support adapted to be contacted by the other of said catch members when its associated sash is closed, said last named catch member being thus adapted to be retained between said surface and the other of said catch engaging portions of the latch member.
